US00D867677S

(12) **United States Design Patent**
Danenber et al.

(10) **Patent No.:** US D867,677 S
(45) **Date of Patent:** ** Nov. 19, 2019

(54) **ANIMAL FEED TUB AND COVER**

(71) Applicant: **PURINA ANIMAL NUTRITION LLC**, Shoreview, MN (US)

(72) Inventors: **Benjamin R. Danenberg**, White Bear Lake, MN (US); **Michael J. Gabriel**, Inver Grove Heights, MN (US); **Michael S. Burr**, Marthasville, MO (US)

(73) Assignee: **PURINA ANIMAL NUTRITION LLC**, Shoreview, MN (US)

(**) Term: **15 Years**

(21) Appl. No.: **29/654,301**

(22) Filed: **Jun. 22, 2018**

Related U.S. Application Data

(62) Division of application No. 29/534,874, filed on Jul. 31, 2015, now Pat. No. Des. 824,602.

(57) **CLAIM**

The ornamental design for a animal feed tub and cover, as shown and described.

DESCRIPTION

This application relates to design application U.S. patent application Ser. No. 29/534,880 filed Jul. 31, 2015 and design application U.S. patent application Ser. No. 29/648,521 filed May 22, 2018. This application also relates to a non-provisional patent application U.S. patent application Ser. No. 14/815,488 filed Jul. 31 2015, the content of which is incorporated by reference herein in its entirety.

FIG. 1 is an isometric view of an animal feed tub and cover showing the new design;

FIG. 2 is a top view thereof;

FIG. 3 is a bottom view thereof;

FIG. 4 is a first side view thereof; and,

FIG. 5 is a second side view thereof.

FIG. 6 is a cross-sectional view of the animal feed tub and cover taken from line 6-6 of FIG. 5.

The broken lines in the figures represent portions of the animal feed tub and cover which are not part of the claimed design.
